CLAIM

I claim the ornamental design for a neck heater, as shown and described.

DESCRIPTION

FIG. 1 is a top-front perspective view of a neck heater; FIG. 2 is a front view of the neck heater of FIG. 1; FIG. 3 is a rear view of the neck heater of FIG. 1; FIG. 4 is a left side view of the neck heater of FIG. 1; FIG. 5 is a right side view of the neck heater of FIG. 1; FIG. 6 is a top view of the neck heater of FIG. 1; FIG. 7 is a bottom view of the neck heater of FIG. 1; and, FIG. 8 is a bottom-right side perspective view of the neck heater of FIG. 1.

(Continued)

The broken lines in the drawings illustrate portions of the neck heater that form no part of the claimed design.

1 Claim, 6 Drawing Sheets
